UNITED STATES PATENT OFFICE.

EDGAR J. KNAPP, OF CHICAGO, ILLINOIS.

STORAGE BATTERY.

SPECIFICATION forming part of Letters Patent No. 716,056, dated December 16, 1902.

Application filed May 19, 1902. Serial No. 107,903. (No model.)

To all whom it may concern:

Be it known that I, EDGAR J. KNAPP, a citizen of the United States, residing at Chicago, in the county of Cook and State of Illinois, 5 have invented a certain new and useful Improvement in Storage Batteries, (Case No. 1,) of which the following is a full, clear, concise, and exact description, reference being had to the accompanying drawings, forming a part 10 of this specification.

My invention relates to storage batteries, and has for its object the provision of improved structural facilities whereby buckling of the storage-battery plates may be avoided; 15 and, generally speaking, it consists of constraining means associated with the corners of the battery-plates that force the said plates to remain in normal planes notwithstanding great tendency to buckle. Buckling in storage-battery plates usually commences at the 20 corners thereof, and in order to furnish the desired constraining means corner-caps are preferably placed over the corners of the plates, such corner-caps being made of substantially rigid sheets of material to furnish 25 the desired constraint, they serving effectually to prevent buckling of the plate-corners. These corner-caps in the preferred embodiment of the invention also serve to secure 30 storage-battery separators, such separators being preferably interposed between the battery-plates and the walls of the caps that are parallel therewith.

I will explain my invention more fully by 35 reference to the accompanying drawings, in which—

Figure 1 is a perspective view of a battery-plate constructed in accordance with the invention. Fig. 2 is a perspective view of a 40 modified form of one of the caps employed for guarding the battery-plates and assembling the separators therewith.

Like parts are indicated by similar characters of reference in both views.

The invention is designed for application 45 to any suitable form of storage-battery plate *a*, and the form of separator *b* may be any suited to the purpose. That shown in Fig. 1 may be composed of sheet-rubber, provided 50 with separating-ribs *c* and apertures *d*, permitting of the circulation of battery fluid and

preventing the dislodgment of active material. The preferred device or agency for preventing the battery-plate from buckling at the corners resides in the triangular corner-caps *e*, preferably separable from the battery-plate and separator, that may, if desired, be formed of sheet-rubber fluted and apertured similarly to the separator. The caps are provided with horizontal and vertical walls *f* and *g*, that engage the horizontal and vertical edges of the battery-plates, and are also provided with side walls *h* and *i*, that lie parallel with the storage-battery plates, the side walls *h* and *i* being preferably triangular, as 60 illustrated, especially for the bottom caps, so that the active material that may fall from the battery-plates will not find a lodging-place upon the caps, which might with certain arrangement of separators result in short circuit. The caps by being made of substantially rigid sheet-rubber most effectively act to maintain the battery-plates in the required 70 shape and where desired also serve to retain the separators in place in the manner indicated in Fig. 1.

It is obvious that departures may be made from the precise embodiment of my invention herein shown without departing from the spirit of the invention, and I do not, therefore, wish to be limited to the precise structure shown; but,

Having thus described my invention, I claim as new and desire to secure by Letters Patent—

1. A storage-battery plate, provided with constraining means at its corner portions for maintaining it in its normal plane against buckling or curling tendencies, the said means being in the form of corner-caps, substantially 85 as described.

2. A storage-battery plate, provided with constraining means at its corner portions for maintaining it in its normal plane against buckling or curling tendencies, the said means 90 being in the form of corner-caps having horizontal, vertical and side walls, substantially as described.

3. A storage-battery plate, provided with constraining means at its corner portions for 95 maintaining it in its normal plane against buckling or curling tendencies, the said means 100

being in the form of corner-caps having horizontal, vertical and side walls, said side walls being triangular, substantially as described.

4. The combination with a storage-battery plate, of a separator therefor, and corner-caps inclosing the corners of the storage-battery plate, the separator being interposed between walls of the caps and a corresponding wall of the storage-battery plate, substantially as described.

5. The combination with a storage-battery

plate, of separable corner-caps therefor, engaging the sides of the battery-plate and preventing the same from departing from the normal plane of the battery-plate, substantially as described. 15

In witness whereof I hereunto subscribe my name this 17th day of May, A. D. 1902.

EDGAR J. KNAPP.
